PORCH GLIDER

Burnard McGehee, McComb, Miss., assignor of
one-third to L. S. McLaren and one-third to
N. B. Gillis, both of McComb, Miss.

Application January 17, 1947, Serial No. 722,509

6 Claims. (Cl. 155—61)

1

This invention relates to an article of furniture and particularly to porch swings or gliders.

Gliders are well known in which the seat portion is supported on a linkage which permits forward and backward movement. However, in many of the prior devices this linkage is somewhat complicated, and furthermore, there is an arcuated component to the path of movement. Also, in these prior devices the forward and backward movement is rather limited. The arcuate movement is unpleasant to some people and for this reason porch swings of this general type are objectionable to them. The present invention provides a simple inexpensive mechanism in a porch glider or swing so that the seat will have a long travel and the path of travel will be substantially rectilinear.

Accordingly, the primary object of invention is to provide an improved glider in which the seat will have a long rectilinear horizontal movement and a smooth stroke.

Another object is to provide a glider of the type described of very simple construction.

A still further object is to provide a glider of the type described which is durable and may be manufactured at low cost.

Other and further objects will be readily apparent from the following description considered in connection with the accompanying drawings, illustrating an embodiment of the invention, and in which:

Figure 1 is a perspective view of the preferred form of my invention;

Figure 2 is an end elevation view of Figure 1;

Figure 3 is a partial sectional elevation on line 3—3 of Figure 2; and

Figure 4 is a detail section on line 4—4 on Figure 2.

The invention resides in the novel construction combination and arrangement of the parts hereinafter described in detail and claimed in the appended claims. The embodiment of the invention selected for the purposes of illustrating the invention comprises a main frame 1, a swingable seat 2, and intermediate swinging or floating spider frames 3 which are swingingly supported by the two ends of the main frame. The two ends of seat structure 2 are in turn swingingly supported from the spiders 3.

The main frame 1 comprises a pair of laterally spaced inverted U-shaped end members 5, each of which includes a front and rear vertical supporting member adjoined by a central horizontal reach portion 11. The horizontal reach portion 11 serves as the support for the seat in a manner which will be presently described. The two end frame members 5 are joined by an integral longitudinal member 19 to constitute an integral frame unit. A substantially horizontal transverse brace member 15 is connected, as by welding or brazing, to the front and rear vertical members of the end

frames 5. The transverse brace members 15 are connected by a horizontal brace member 16, the ends of the latter being joined to the midpoints of the transverse brace members 15 of the respective end frames 5 by welding, brazing or otherwise securing them to U-shaped plates 43 fixed to the brace member 15.

As previously mentioned, the seat 2 is swingingly supported from the upper horizontal reaches 11 of the end frames 5. To this end, a pair of journal bearings 22 in the form of short cylindrical sleeves are attached to the under side of the horizontal reaches 11, as by welding. These bearings are adapted to receive the hooked ends 24 of swing rods 26. These rods 26 also have horizontally disposed hooked ends 28 which are journaled in cylindrical sleeve bearings 30 fixed to the bottom side of a strut 32, which is fixed to and forms a part of intermediate spider frames 3 previously mentioned. The bearings 30 are so spaced that the rods 26 are substantially parallel. The spider frames 3 comprise a plurality of U-shaped yoke members 36 which are fixed together in back-to-back relation so that they form, in general, an X-shaped member. A strut 35 is fixed to the upper ends of the yoke members 36 in the same manner that strut 32 is fixed to the lower ends of the yoke members 36. It will be readily understood that the yoke members 36 and the struts 32 and 35 can be secured together in any manner such as bolting, welding or brazing. It will be apparent from the above description that the spider frames 3 are pivotably supported on the rods 26 in such a manner that the spider frames can be moved back and forth relative to the end frames 5 without substantially changing the angular position of the spider frames.

Suitable guide means are provided for maintaining the spiders 3 in planes parallel to the planes of the end frames 5 during the movement of the swing seat 2. To this end, the upper horizontal reaches 11 of the end frames 5 have depending spaced parallel plates 42 which are the opposite legs of a U-shaped member welded or brazed to the opposite sides of the reaches 11 and adapted to embrace the upper ends of the spiders 3. Likewise, another U-shaped member, the opposite legs of which are spaced parallel plates 43, is fixed to the horizontal brace members 15 and extends upwardly therefrom to embrace the lower end of the spiders. Anti-friction rollers 40 are journaled on bolts 38 which extend through the members 35 and 32 and are adapted to engage the plates 42 and 43, respectively, for the purpose of guiding the spiders 3 during their forward and backward movement.

The seat 2 is swingingly supported from the upper end of the spider frames 3 by means of rods 50. The upper and lower ends respectively

of these rods extend at right angles to the main portion of the rods and engage spaced bearings 51 affixed to the member 35 and bearings 55 which are attached to extensions 56 constituting a part of the frame of the seat structure 2. The seat 2 is made of tubular elements and the members 56 may be integral extensions thereof or may be separate elements attached by welding or brazing to the structural elements of the seat. Since the seat is of conventional construction it forms no part of the invention and no further description is necessary.

From the foregoing description it will be apparent that a person occupying the seat 2 can push the same backward and forward causing the 15 spider frames 3 to swing on rods 26 and the seat 2 to swing on rods 50. The manner in which the rods are pivotally connected to the end frames 5, the spider frames 3 and the seat 2 is such as to constitute parallelograms so that there is substantially no arcuate component to the swinging movement of the seat. In other words, the movement of the seat is in a rectilinear path. The anti-friction rollers 40 engaging plates 42 and 43 maintain the spider frames 3 in fixed planes and prevent the spider frames from tilting. It will be apparent that because of the great length of the rods 26, 50 and the parallelogram arrangements mentioned the arcuate component of the movement of the spider frame 3 will be extremely small while the seat will have a very long smooth gliding movement. It will, of course, be apparent that minor changes can be made while still embodying the broad aspect of the present invention.

Although the invention has been described in considerable detail, it will be apparent to those skilled in the art that many variations are possible without departing from the inventive concept except as limited by the appended claims.

Having thus described the invention, what is claimed is:

1. In an article of furniture the combination of a main frame, including laterally spaced end portions, vertical spider frames swingingly supported at spaced points on their lower ends from said end portions and a seat structure swingingly supported at each of its ends from the upper ends of said spider frames and means for permitting movement of said spider frames relative to said frame in directions transverse of said seat structure while preventing said spider frames from turning end-for-end about a horizontal axis.

2. In combination in an article of furniture, a frame having horizontal supporting end portions, a seat structure suspended for swinging movement from said horizontal portions, a spider frame for each end of said seat structure, supporting members pivoted at their upper ends to said horizontal portions of said frame and at their lower ends to the lower ends of said spider frames in parallel relation, a second set of parallel members having their upper ends pivotally connected to the upper end of said spider frames and having their other ends pivotally connected to said seat structure and means carried by said frame for permitting said spider frames to move transversely of said frame and preventing changing of their angular relation with respect to the transverse portion of said frame.

3. In combination in a glider, a seat structure, a frame member having rectangular end portions and a longitudinal interconnecting element

adapted to rest on a supporting surface or floor, a vertical floating intermediate member, links pivotally connected at their upper ends to said frame member and at their lower ends to said floating member, additional links connected at their upper ends to said floating member and at their lower ends to said seat structure, all of said links being disposed in parallelism whereby backward and forward movements of said seat structure will be confined substantially to rectilinear movement, and means carried by said frame member for preventing said floating member from turning out of its plane of movement.

4. In combination in an article of furniture, a main frame including spaced rectangular end supporting portions and a longitudinal interconnecting element, floating members for each end of said supporting portions, said floating members being supported at their front and rear from one of said end supporting portions, guide means carried by each of said end frame portions, roller means carried by each of said floating members and engaging said guide means, and a seat structure swingingly supported at each of its ends from one of said floating members.

5. In combination in an article of furniture, a main frame including an inverted substantially U-shaped end supporting portion, a floating member, a seat structure, links having their upper ends pivotally connected to said end supporting portion and their lower ends pivotally connected to said floating member, whereby said floating member is adapted to swing within the plane of said U-shaped end supporting portion, additional links pivotally connected at their upper ends to the upper end of said floating member and at their lower ends to said seat structure, guide means carried by said end supporting portion comprising spaced parallel plate members 40 fixed to said end supporting portion, and roller means carried by said floating member adapted to engage said spaced parallel plate members.

6. In combination in an article of furniture, a frame comprising a longitudinal member and inverted substantially U-shaped end supporting portions each having a horizontal element, a seat structure, intermediate means having vertically spaced parallel horizontal members and interconnecting means therefor disposed adjacent and parallel to each of said end portions, a pair of links pivotally connected at their upper ends to the respective horizontal elements of said frame and at their lower ends to the lower of said horizontal members of said intermediate means, and a second set of links connected at their upper ends to the respective upper horizontal members of said intermediate means, all of said links being disposed in parallelism whereby backward and forward movements of said seat structure will be confined substantially to rectilinear movement.
